UNITED STATES PATENT OFFICE.

GEORGE E. KENT, OF WOODLAND, MAINE, ASSIGNOR TO MURPHY IRON WORKS, OF DETROIT, MICHIGAN, A CORPORATION OF MICHIGAN.

ROUST-BOX COVER.

Application filed March 2, 1922. Serial No. 540,485.

To all whom it may concern:

Be it known that I, GEORGE E. KENT, a citizen of the United States, residing at Woodland, in the county of Washington and State of Maine, have invented certain new and useful Improvements in Roust-Box Covers, of which the following is a specification.

As is well known, certain types or kinds of furnaces are provided with holes conveniently located just above the grate through which a roust-bar is inserted at intervals by the fireman as may be required for stirring up the bed of fuel to facilitate its combustion.

Such holes are ordinarily fitted with castings, known as "roust-boxes" extending through the front masonry wall, and a flange for each hole is bolted to the furnace front-plate, being equipped with a movable cover.

When it is desired to insert the roust-bar and project it through the roust-box to perform its usual fuel stirring or agitating function, the rockingly mounted cover is temporarily swung around out of the way by hand or by the roust-bar, thus uncovering the aperture, and a special projection on the flange prevents an unintentional return of the cover to normal position over the hole.

When the rousting operation has been completed, the operator rocks the cover back into place thus again covering or closing the hole.

If the attendant or fireman is comparatively expert, he can open and close the roust-holes, that is, manipulate their covers, by the roust-bar itself, but ordinarily these covers must be operated by hand, thus requiring additional work or movements which are more or less tedious constituting somewhat of a nuisance or annoyance particularly when the fireman is busy and is required to attend to a number of furnaces or stokers.

The leading aim of the present invention, is, therefore, to provide a simple roust-box cover which can be easily actuated by the roust-bar and which will automatically close when the fuel-bed stirring operation has been completed and the roust-bar withdrawn.

A further purpose of the invention is to supply a structure of this type provided with a sight or pilot means to assist the fireman in locating the exact point for the in-

sertion of the bar, which operation in the new appliance automatically opens the cover.

An additional object of the invention is to provide an appliance of this general character which is simple in construction, and economical to manufacture, which is effective in operation, and which is unlikely to become damaged or injured in ordinary service.

To enable those skilled in this art to have a full and complete understanding of this invention both from structural and functional standpoints, I have illustrated in the accompanying drawing, a desirable and preferred embodiment of the invention and in the two figures of such drawing, like reference characters have been employed to designate the same parts.

In this drawing,

Figure 1 is a fragmentary face view of a part of the front-plate of a furnace or stoker illustrating in elevation on the new type or style of roust-box construction; and

Figure 2 is a vertical section on line 2—2 of Figure 1, the parts being viewed in the direction indicated by the arrows.

Referring to this drawing for an understanding of the details of the structure, it will be perceived that the metal front or face plate of the stoker or furnace has been given the reference character 11, such plate being apertured at 12 for the reception of the front end of a circular or tubular roust-box 13 through which the roust-bar, not shown, is adapted to be temporarily introduced into the furnace to perform its usual work in the hands of the operator.

By means of a pair of threaded studs 14 and 15 having heads incorporated in the face-plate and a pair of coating nuts 16 and 17, a suitably-shaped flange member 18 surrounding the hole is fastened to the front of the plate.

Such circular flange element has a slightly-tapered or outwardly-flaring hole 19 therethrough in register with and of substantially the same diameter as the passage through the roust-box, such construction facilitating the introduction or insertion of the roust-bar, all as will be readily understood.

A pair of companion or cooperating cover elements 21 and 22 are rockingly or swingingly mounted at their upper ends on a hinge-pin 23 screwed into a threaded hole 24 in the flange member and having a head 25

preventing dislodgment of the cover members.

The one cover element 21 is of general semi-circular contour with an apertured ear 5 26 of about half its thickness constituting the simple means by which it is mounted for oscillation on the supporting hinge-pin, whereas, the mating or associated cover member 22 is of similar but reversed shape 10 with a perforated lug 27 mounted on the hinge-pin just outside of the ear 26, whereby the two correlated cover segments are capable of independent rocking or swinging movements.

15 It is to be noted that the axis of the hinge-pin is substantially in the plane of the flat face of each cover part, and, consequently, by reason of their own weights, these two members when unrestrained, rock or swing 20 down until their corresponding plane faces engage one another, as is shown in full lines in Figure 1.

Stated somewhat otherwise, when the cover is operative to close the passage 25 through the roust-box, the straight edge faces of both elements, bear on one another directly below the axis of the hinge-pin and in register with the vertical diameter of the round hole 12 and that of the correspondingly shaped passage through the roust-box.

At the center of this two-part cover or shield there is a round, light or pilot hole through which the light of the fire within the furnace may be seen, such aperture being composed of two matching or registering semi-circular holes 28 and 29 in the contacting edges of the pair of cover elements.

In order that the wall around such sight aperture may be thin to facilitate the passage 40 of the light rays therethrough, and in order also to provide simple and effective means whereby the end of the roust-bar may be used to separate such cover members to permit its introduction into the furnace 45 through the roust-box and to facilitate its withdrawal from the furnace, the two cover elements on their outer faces are provided with matching semi-egg-shaped flaring recesses 31, 32, leading to the central sight hole 28, 29, and on their inner faces they have similar inwardly-widening registering or mating cavities 33, thus making the intermediate portion of the cover wall supplied with the small, round, sight hole comparatively or relatively thin.

As will be readily understood, both the inner and outer flaring cavities contribute to making the light in the sight-hole conspicuous, and, in addition, the outer recess 60 acts as a guide for the end of the roust-bar, the inward movement of which when aimed at the spot of light automatically engages and separates the cover parts as depicted in dotted lines in Figure 1, the roust-bar being similarly shown and marked with

the reference character 34, these cover sections by gravity acting on them immediately and automatically closing the hole as soon as the bar is withdrawn.

The fronts of many furnaces are in the 70 dark and the fireman frequently encounters difficulty in quickly locating the roust-holes, but with this novel and improved structure, he merely jabs the end of the bar at the apex of the generally-conical outer surface which 75 action pushes the parts of the cover apart permitting its continued travel into the furnace for action on the fuel bed. Of course as soon as the bar is withdrawn, the cover automatically closes by reason of the action 80 of gravity on its companion elements.

Those skilled in this art will readily understand that the appliance shown and described in detail is only one desirable embodiment of the invention and that the latter is susceptible of a variety of satisfactory embodiments. Accordingly, many minor mechanical changes may be made in the structure shown without departure from the heart and essence of the invention and without the sacrifice of any of its substantial 90 benefits and advantages.

I claim:

1. In a furnace roust-box cover construction, the combination of a support adjacent to the passage through which a roust-bar is adapted to be introduced into the furnace, and a plurality of cover elements rockingly mounted on said support and unitedly forming a cover for said passage by gravity, said elements having mating recesses in their adjacent edges forming a pilot hole, the exterior and interior surfaces of said elements converging toward said pilot hole, whereby to facilitate the passage of light therethrough and whereby a roust-bar aimed at said pilot hole will engage said exterior converging purposes and rock said elements apart permitting its introduction into said passage.

2. In a furnace roust-box cover construction, the combination of a support adjacent to the passage through which a roust-bar is adapted to be introduced into the furnace, and a plurality of cover-elements rockingly mounted on said support and unitedly forming a cover for said passage by gravity, said elements having mating recesses in their adjacent edges forming a pilot hole, the exterior surfaces of said elements converging toward said pilot hole, whereby a roust-bar aimed at said pilot hole will engage said exterior converging surfaces and rock said elements apart permitting its introduction into the furnace.

3. In a furnace roust-box cover construction, the combination of a support adjacent to the passage through which a roust-bar is adapted to be introduced into the furnace, and a plurality of cover elements movably

mounted on said support and unitedly forming a cover for said aperture, said cover elements having a sight hole therethrough adjacent to their meeting edges to facilitate the insertion of the end of a roust-bar aimed at such hole to separate the cover elements and thus open up said aperture.

4. A furnace roust-box cover construction, comprising in combination, an apertured support through which the roust-bar is adapted to be introduced into the furnace, and a plurality of cover members movably mounted on said support and adapted to unitedly constitute a cover for said aperture, said members having surfaces located to facilitate the insertion of the end of the bar between and cause a wedging separating action on the cover members to open up the passage.

5. A furnace roust-box cover construction, comprising in combination, an apertured support through which the roust-bar is

adapted to be introduced into the furnace, and a plurality of cover members rockingly mounted on said support and adapted to unitedly constitute a cover for said aperture, said members having surfaces located to facilitate the insertion of the end of the bar between and cause a wedging separating action on the cover members to open up the passage.

6. A furnace roust-box cover construction, comprising in combination, an apertured support through which the roust-bar is adapted to be introduced, a pivot pin on said support, and a plurality of cover members rockingly mounted on said pin and adapted to unitedly constitute a cover for said aperture, said members having surfaces located to facilitate the insertion of the end of the bar between and cause a wedging separating action on the cover members to open the passage.

GEO. E. KENT.
